BALFOUR BRAMWELL, OF BELFAST, IRELAND

VOLUMETRIC-DISPLACEMENT APPARATUS SUITABLE FOR CONTROLLING THE SUPPLY
OF GAS FOR CHLORINATING WATER OR SIMILAR PURPOSES

Application filed December 15, 1927, Serial No. 240,326, and in Great Britain March 16, 1927.

This invention relates to volumetric displacement apparatus for regulating the supply of gas for the chlorinating of water or other purposes.

5 This regulation is effected by a water displacement apparatus to which the gas is supplied at constant pressure, so that each oscillation of the water in the displacement vessel represents a definite volume of gas.

10 Other displacement apparatus for the purpose of measuring and controlling the supply of gas are known, in which the total gas supplied in a definite time is dependent on the number of visible oscillations of the water 15 in the displacement vessel in that time. The difficulty, however, is to obtain uniform and regular displacement volumes of gas at each oscillation at different speeds of oscillations.

The object of this invention is to provide 20 a construction of such apparatus which will give equal and positive displacements at varying speeds and prevent bubbling, so that the total number of oscillations is in direct proportion to the total volume of gas delivered 25 by the apparatus.

The apparatus constituting the present invention comprises a displacement vessel and a U-shaped venting tube so connected therewith that upon the displacement of a column 30 of liquid within the vessel to a predetermined extent by the pressure of the gas to be measured the venting tube becomes unsealed and permits the escape of a definite volume of the gas before the reduced pressure re-establishes 35 initial conditions and re-seals the vent tube. In these respects the apparatus does not differ from known devices, but in the present invention the relation between the venting or sealing tube and the displacement vessel is 40 such that at each pulsation of the liquid in the displacement vessel a definite volume of liquid as well as a definite volume of gas is delivered, as one limb of the venting tube is carried through the wall of the displacement 45 vessel and only one end of the tube is open to the interior of the vessel.

An apparatus embodying the invention is shown in vertical cross section in Fig. 1 of the accompanying drawings, Fig. 2 being 50 a similar view of a modified construction. In

the construction of Fig. 1 *a* is the displacement vessel which is closed at the top and open at the bottom, and is contained in a closed water vessel *b* into which the water supply is led through a pipe *f*. Both *a* and *b* are made of transparent material, such as glass or celluloid, so that the rate of displacements or oscillations can be observed and regulated by the gas supply, which latter is led to the displacement vessel by a pipe *e* on which is fixed a regulating valve (not shown) to control the amount of gas admitted.

The use of a U-tube *c d* inside the displacement vessel *a* and its arrangement and proportions constitute the important feature and 55 novelty of this invention.

The upper end of the short leg of this U-tube *c d* inside the displacement vessel is of considerably larger diameter than the tube, the effect of which is that immediately 60 the water rises a little past the top, a comparatively large volume overflows and forms a water-seal which prevents further gas escape and prevents bubbling. The seal remains until the further supply of gas again 65 displaces the water in the vessel *a*.

Another feature of the invention is the advantageous effect of the U-tube. This is arranged so that the bottom edge of the vessel *a* extends somewhat lower than the bottom 70 of the U-tube *c d* and gives sufficient time for the complete emptying of the gas from *a* without any bubbling.

Assuming that the water is at the level *L*₁ 75 in the displacement vessel *a*, the gas entering 80 the vessel through pipe *e* gradually depresses the water level in vessel *a* and simultaneously the water in the left or funnel leg *c* of the U-tube is displaced up the right leg *d* by the pressure of the entering gas, and when the 85 water level in the left leg of the U-tube reaches level *L*₂ the U-tube seal is forced and the gas escapes freely through the leg *d*. The 90 consequent sudden release of pressure within the displacement vessel permits the water in vessel *a* to rise again to level *L*₁ and reestablish the seal. It will be seen that at each 95 pulsation a definite volume of water and a definite volume of gas escape through the leg *d* of the U-tube.

It is not necessary to use an outer containing vessel *b* provided the water flows sufficiently quickly through the inlet pipe *f* on each pulsation within the displacement vessel *a*. Accordingly in the modified construction shown in Fig. 2 the outer vessel *b* is omitted and the water supply pipe *f* is taken direct to the displacement vessel *a* and has a cross section comparable with that of the vessel *a* itself.

Having thus described the nature of the said invention and the best means I know of carrying the same into practical effect, I claim:—

1. An apparatus of the character herein referred to, comprising a displacement vessel closed at its upper end, a U-shaped vent tube having one limb provided with an enlarged end and extending into the displacement vessel to a point adjacent the upper end of the latter with its bend adjacent the lower end of said vessel and its other limb extending outside the said vessel, means for admitting a liquid to the lower portion of said vessel, and means for admitting gas under pressure to the upper portion of said vessel.

2. An apparatus of the character herein referred to, comprising a displacement vessel open at its lower end and closed at its upper end, a U-shaped vent tube disposed within the said vessel with the end of one limb adjacent the upper end of the vessel and its other limb extending outside of said vessel, the bend of the U-tube being above the lower edge of the displacement vessel, and means for admitting gas under pressure to the upper portion of said vessel.

In testimony whereof I have signed my name to this specification.
